UNITED STATES PATENT OFFICE.

JOHN CLIFFORD WHITRIDGE AND GEORGE T. JOHNSON, OF COLUMBUS, OHIO, AS
SIGNORS TO THE BUCKEYE STEEL CASTINGS COMPANY, OF COLUMBUS, OHIO.

COUPLER SHANK AND YOKE CONNECTION.

Application filed January 28, 1927. Serial No. 164,303.

In the usual type of connection between a car coupler shank and the yoke, the key is substantially rigid in the shank and, when the shank moves angularly, the key moves from its bearing in one side of the yoke and the full load is taken on its bearing in the other side of the yoke, putting a twist action in the coupler butt and an eccentric load on the yoke. The present invention overcomes the twist action of the key and equalizes the load on the two sides or jaws of the yoke in all angular positions of the shank, permitting the weight of the yoke and the coupler to be reduced and minimizing wear on the key. The invention is illustrated in the accompanying drawing and will be hereinafter fully described, the novel features being particularly pointed out in the appended claims.

In the drawings, Figure 1 is a horizontal section through a shank and yoke connected according to the present invention; Figure 2 is a longitudinal vertical section; Figure 3 is a detail of the bearing block; Figures 4, 5 and 6 are details of the equalizer or swivel block; Figure 7 is a horizontal section showing a variation.

The yoke 1 has the jaws or side members 2 of the usual form to receive the coupler shank 3 and slots 4 and 5 are formed in the yoke jaws and the shank, respectively, to receive the key 6; the shank being recessed at the rear of the slot, as shown at 7. Within the recess or chamber 7, a bearing block 8 is disposed in contact with the butt or rear wall of the shank, and between the bearing block and the key is an equalizer or swivel block 9. The bearing block is of greater vertical extent than the key slot and its forward face presents a vertically extending horizontally convex surface 10, while the equalizer has a vertically extending horizontally concave bearing surface 11 on its rear side seating against said convex surface, and it will be noted, upon reference to Figure 1, that the apex of the surface 10 is approximately in a plane touching the rear end walls of the slots 5 in the shank. It will also be noted that the bearing surfaces 10 and 11 are nearly equal in extent to the inside dimensions of the shank while the usual key bearing and wearing surface are only the thickness or height of the key. The front face of the equalizer is vertically con-

cave, as shown at 12, to engage the rear edge of the key and extends practically the full width of the coupler shank, the formation producing stop lugs or horns 13 which project into the slots 5 in position to engage the rear walls thereof. The equalizer and the bearing block are thus prevented from being jammed or distorted in the event of excessive swinging of the shank due to failure of either the key or the yoke. The lugs 14 on the swivel block 9, Figs. 1 and 6, are provided to help guide the key to its proper bearing for draft after the coupler has been in the buff position. The wear due to the angular movement of the shank all comes on the contacting bearing faces 10 and 11, and because of the area of these surfaces the life and efficiency of the device is prolonged.

It will be seen that by increasing the horizontal length of the stop lugs or horns 13 and so proportioning the spacings of the yoke jaws or side members 2 of the yoke, a substantial increase in bearing between key and equalizer can be provided and a greater bearing between these parts, thus obtained in this type of construction than the ordinary type heretofore used.

In assembling the coupler and yoke, the bearing block is first inserted sidewise through a slot 5 and then turned through an angle of 90 degrees and pushed into contact with the inside bearing face of the coupler butt. The bearing block 8 being so proportioned and shaped that at any point its actual thickness is less than the vertical height of the slot 5, makes this possible although the overall depth of the bearing block 8 may be greater than the height of the slot 5. The equalizer is then inserted in the same manner and turned into proper engagement with the bearing block, after which the coupler is inserted in the yoke and the key placed in position. The equalizer 9 being so proportioned and shaped that at any point its actual thickness is less than the vertical height of the slot 5, makes this possible although the overall depth of the swivel block 9 is greater than the height of the slot 5. It will be seen that the equalizer and the bearing block cannot be removed or lost unless first turned through 90 degrees and it is, therefore, possible to make the slots in the shank longer than usual to provide for greater angularity without diminishing the efficiency of the locking ar-

angement. Also by this method of assembling and locking the parts, although they may be displaced relatively to each other, never move from their normal positions sufficiently to effect their functioning as described, the parts cannot be removed or lost until the key is removed and no bolts, rivets, or pins are required to lock the various parts in position. An additional locking feature is provided by proportioning the bearing surfaces 10 and 11 so that the distance "a" is always greater than the distance "b".

The bearing block may be integral with the coupler shank and, in Figure 7, we have shown the coupler butt 14 cast with a convex projection 15 on its inner face which will serve all the functions of the bearing block 8. The equalizer may be formed integral with the key if the height of the bearing face 11 be reduced so that it may be inserted through the slot without turning.

Having fully described our invention what we claim as new and desire to secure by Letters Patent, is:—

25 1. The combination of a slotted coupler shank, a slotted yoke, and a key inserted therethrough, said shank provided with a vertically extending horizontally convex bearing surface at the rear of the slots 30 therein, and an equalizer between the key and said surface having a concave rear face seating on the bearing surface.

2. The combination with a slotted coupler shank, a slotted yoke, and a key inserted 35 therethrough, of a bearing block within the shank in contact with the butt thereof and having a vertically extending horizontally convex front bearing face, and an equalizer having its front face engaging the rear 40 surface of the key and provided on its rear side with a vertically extending horizontally

concave face seating on the convex face of the bearing block.

3. The combination with a slotted coupler shank, a slotted yoke, and a key inserted 45 therethrough, of a bearing block within the shank in contact with the butt thereof and having a vertically extending horizontally convex front bearing face, and an equalizer 50 having its front face engaging the rear surface of the key and provided on its rear side with a vertically extending horizontally concave face seating on the convex face of the bearing block, the area of the contacting surfaces of the bearing block and the 55 equalizer approximating the inside dimensions of the shank.

4. An equalizer block having a horizontal extending vertically concave front key bearing surface and a vertically extending horizontally concave rear bearing surface, the area of the rear bearing surface having dimensions to approximate the inside dimensions of the shank and horizontal extending lugs to enter key slots in a coupler 60 shank.

5. An equalizer block having a horizontally extending vertically concave front key bearing surface and a vertically extending horizontally concave rear bearing surface, 70 said block being of less thickness at one point than the height of the key slot in a coupler shank through which it is to pass and of a width just sufficiently less than the inside width of the coupler shank to allow 75 it to be turned through 90 degrees and seated.

In testimony whereof, we have signed this specification.

JOHN CLIFFORD WHITRIDGE.
GEORGE T. JOHNSON.
